(57) **CLAIM**

The ornamental design for a replaceable fan assembly, as shown and described.

DESCRIPTION

FIG. 1 is a front, top, right side, exploded isometric view of a replaceable fan assembly, showing the new design;
FIG. 2 is a front, right side perspective view thereof;
FIG. 3 is a rear, right side perspective view thereof;
FIG. 4 is a front elevational view thereof;
FIG. 5 is a right side elevational view thereof;
FIG. 6 is a left side elevational view thereof;
FIG. 7 is a top plan view thereof;
FIG. 8 is a bottom plan view thereof; and,
FIG. 9 is a front, left side, isometric view thereof, shown in an environment of use.
The broken lines depict environmental subject matter only and form no part of the claimed design.
